CLAIM

The original design for a customer operated visual responsive order stand for drive-through restaurants, as shown and described.

DESCRIPTION

FIG. 1 is a front elevational view of a customer operated visual responsive order stand for drive-through restaurants showing my new design, with the broken line showing for illustrative purposes only and forming no part of the claimed design;

FIG. 2 is a left side elevational view thereof, with the right side being a mirror image; and,

FIG. 3 is a rear elevational view thereof, with the top and bottom being flat and unornamented.

Fig. 3

Fig. 2
